SHANK FOR SEPARABLE LINK CUFF-BUTTONS.

1,188,211.

Specification of Letters Patent. Patented June 20, 1916.

Application filed February 16, 1916. Serial No. 78,608.

To all whom it may concern:

Be it known that I, CARL E. SKOOG, a citizen of the United States, and a resident of Providence, in the county of Providence and State of Rhode Island, have invented new and Improved Shanks for Separable Link Cuff-Buttons, of which the following is a full, clear, and exact description.

10 Among the principal objects which the present invention has in view are: to provide one-piece shanks having male and female engaging portions; to provide a spring engaging member for the female portion, 15 the resiliency of which is incorporated therein; and to provide button shanks of the character mentioned adapted to be manufactured by automatic machinery.

Drawings.—Figure 1 is a view of a metal 20 blank from which the button shanks are made; Figs. 2 and 3 are vertical sections of metal members, showing the initial steps in the process of making the shanks; Figs. 4 to 8 inclusive are vertical sections of metal 25 members, showing the progressive steps in the formation of the female fastening shank; Fig. 9 is an enlarged top view of the female shank, the dotted lines in said figure indicating the width of the saw cut forming 30 the gripping jaws of the female shank; Fig. 10 is a similar view, showing the female shank after the saw cut has been made and when the shank is completed; Fig. 11 is a vertical section showing the metal member 35 in a preliminary stage of forming a male shank; Fig. 12 is a vertical section of the completed male shank; Fig. 13 is a cross section of cuff buttons constructed and arranged in accordance with the present invention and united as in service, the dotted 40 lines in said figure being used to indicate the folded portions of a shirt cuff.

Description.—As seen in the drawings, shanks when constructed in accordance with 45 the present invention, are formed from circular blanks of metal, as shown in Fig. 1 of the drawings. A series of operations are performed on these blanks to mold the same to the shapes shown in cross section by Figs. 2 and 3 of the drawings. The shapes as 50 shown in Fig. 3 of the drawings are then either punched to form crown openings 18, as seen best in Fig. 9 of the drawings, or are pressed to form nibs 19, as shown best in 55 Fig. 11 of the drawings.

The present invention is principally concerned with the manufacture of what is herein termed the female shank. In order to secure the requisite resiliency in the gripping portions thereof, the metal forming 60 the throat 20 of the shank and the under side 21 are hammered to temper the same to provide the necessary resiliency therein for the closure of the jaw members as herein described. With this purpose in view, the 65 shank head and the opening 18 in the upper side thereof, as originally formed, are slightly elliptical or elongated. In this manner is provided the necessary excess of metal in the upper side 22 of the shank, so 70 that when permitted to spring together, the side portions thereof form the normal circular fastener opening 23, as seen best in Fig. 10 of the drawings. To guide the operator in making the saw-cut 24, the opening 18 is provided with a nick 25.

In the subsequent operations wherein are formed the throat 20 and the shank head having the under side 21 and upper side 22, 80 said throat is forced into a true cylindrical form. Owing to this, a tension in the metal forming the shank head is produced, tending to draw the metal to a circular shape corresponding with the curvature of the cylindrical throat 20. This tension is relieved when 85 the saw-cut 24 is made in the said head, by permitting the metal at the sides of the saw-cut to spring together to partly close said saw-cut, as will be seen by comparison of the proposed saw-cut, as indicated by dotted 90 lines in Fig. 9 of the drawings, and by the completed saw-cut 24, as seen in Fig. 10 of the drawings.

The nib 19 with which the male shank is provided is pressed up from the head of the 95 shank, as shown best in Fig. 12 of the drawings. The nib 19 has a throat 26 formed therein to receive the edges of the resilient side portions of the female shank when the nib is forced through the opening 21 therein. 100

Claims:

1. A shank as characterized comprising a laterally extended hollow head having under and upper sides, said upper side having a central opening and slots radiating therefrom, the metal of said head being tempered to form separable resilient side portions for gripping a threated member when inserted in said opening. 105
2. A one-piece shank comprising a base 110

flange, a hollow head having juxtaposed upper and lower sides, said upper side having a central opening, and slots radiating therefrom to the periphery of said head to 20
5 form separable resilient side portions for gripping a throated member when inserted in said opening, in combination with a second one-piece shank having a flange base, a head, and throat portion corresponding with 25
10 the first-mentioned shank and provided with a solid throated nib integrally formed with and extended from the center of said head, said nib being insertible in said opening and adapted to slightly separate the resilient side 30
15 portions of the first-mentioned shank during the passage therethrough.

3. A one-piece shank embodying a base flange, a hollow head laterally extended, and

a throated section separating said flange and head, said head having an upper side and a lower side, said sides being centrally spaced apart, said upper side having a central opening and two slots alined and extending radially from said opening and encompassing the outer edges of said head, the metal comprising said head being rendered resilient to permit the portions of said upper side to separate for the passage of a nib of a companion shank to hold the same.

In testimony whereof I have signed my name to this specification in the presence of two subscribing witnesses.

CARL E. SKOOG.
